US00D873800S

(12) **United States Design Patent** (10) **Patent No.:** **US D873,800 S**
(45) **Date of Patent:** **** Jan. 28, 2020**

(54) **REMOTE CONTROL FOR AN ELECTRONIC COMPONENT**

(71) Applicant: **Harman International Industries, Incorporated**, Northridge, CA (US)

(72) Inventors: **Royce D. Channey**, Ann Arbor, MI (US); **Gavzhang Zhang**, Shanghai (CN)

(73) Assignee: **Harman International Industries, Incorporated**, Northridge, CA (US)

(**) Term: **15 Years**

(21) Appl. No.: **29/622,788**

(22) Filed: **Oct. 19, 2017**

(51) LOC (12) Cl. **14-03**

(52) U.S. Cl.

USPC **D14/218**

(57) **CLAIM**

The ornamental design for a remote control for an electronic component, as shown and described.

DESCRIPTION

FIG. 1 is a perspective view of a remote control for an electronic component illustrated with the strap in a closed position showing our new design;

FIG. 2 is a front elevation view thereof;

FIG. 3 is a rear plan view thereof;

FIG. 4 is a side elevation view of one side thereof;

FIG. 5 is a side elevation view of the opposite side thereof;

FIG. 6 is a top plan view thereof;

FIG. 7 is a bottom plan view thereof;

FIG. 8 is a perspective view of the remote control illustrated with the strap in an open position;

FIG. 9 is a front elevation view thereof;

FIG. 10 is a rear elevation view thereof;

FIG. 11 is a side elevation view of one side thereof;

FIG. 12 is a side elevation view of the opposite side thereof;

FIG. 13 is a top plan view thereof; and,

FIG. 14 is a bottom plan view thereof.

1 Claim, 8 Drawing Sheets
